UNITED STATES PATENT OFFICE.

FREDERICK STRATTNER, OF SALISBURY, MARYLAND.

DEVICE FOR FILLING CANS.

SPECIFICATION forming part of Letters Patent No. 690,790, dated January 7, 1902.

Application filed March 21, 1901. Serial No. 52,218. (No model.)

To all whom it may concern:

Be it known that I, FREDERICK STRATTNER, a citizen of the United States, residing at Salisbury, in the county of Wicomico and State of Maryland, have invented certain new and useful Improvements in Devices for Filling Cans; and I do hereby declare the following to be a full, clear, and exact description of the invention, such as will enable others skilled in the art to which it appertains to make and use the same.

My invention relates to certain improvements in apparatus for filling cans, jars, &c., with the requisite liquid after placing therein fruits, vegetables, fish, &c. It has for its object to do this in an expeditious and effective manner; also, to provide for gaging or predetermining the amount of the liquid, syrup, &c., it is desired to introduce or put into the can, jar, &c., preliminary to soldering, sealing, or corking the same; also, to effect the ready handling of the cans, &c., or the dipping thereof into the receptacle or tank containing said liquid, &c., to be filled or put thereto, and similarly to provide for the removal of said cans, &c. It also promotes simplicity and convenience and lessens cost of manufacture.

It consists of the novel features of construction and the combinations of parts including their construction, all substantially as hereinafter more fully disclosed, and specifically pointed out by the claims.

In the accompanying drawings, illustrating the preferred embodiment of my invention, Figure 1 is a sectional elevation. Fig. 2 is a plan view. Fig. 3 is a transverse vertical section. Fig. 4 is a detached perspective view of the carriage for dipping the cans, &c. Fig. 5 is a detached similar view of the tray. Fig. 6 is a longitudinal section of a modification disclosing an endless conveyer for the dipping-carriage. Fig. 7 is a sectional view on the line $\alpha\alpha$ of Fig. 3.

Latitude is allowed herein as to details, as they may be changed or varied at will without departing from the spirit of my invention and the same yet remain intact and be protected.

In carrying out my invention I provide a suitable receptacle or tank 1 to hold the re-

quired liquid, syrup, &c.—as, for instance, for fruits, vegetables, fish, &c.—as may be desired for canning or bottling. Within the tank or receptacle 1 may be placed a coil of 55 pipe 2, resting upon its bottom and extending out through the sides of said tank for suitably connecting it up with a steam boiler or generator for heating the contents of said tank or receptacle. Preferably said tank or receptacle has its opposite ends inclined each from the top edge inward and downward to the bottom, as at 3, and its lateral top edges are provided with inclined boards or guards 4, sloping toward the tank to catch and drain the 60 drippings falling thereon in the filling and handling of the cans, &c., into the tank or receptacle.

An inclined guideway or track 5 is arranged within the tank or receptacle 1 at one end, 70 comprising opposite laterally-grooved bars or rails 5^a 5^b for the guidance of a carrier or carriage 6, mounted to travel therebetween, presently more fully referred to. The guideway or track 5 is arranged in a raised position with 75 relation to the end of the tank, being supported at its higher end upon preferably screw-threaded bolts or pivots 5^b, projecting from said end and extending through the rails thereof. The lower ends of the rails of said 80 track or guideway have passing through and adapted to work in them screws 6^c, bearing in the bottom of the tank 1 and extended upward unthreaded and having heads or otherwise suitably adapted for convenient manipulation. The purpose of this arrangement is to provide for the vertical adjustment or raising and lowering the lower ends of the track or guideway, according to the depth it may be desired to dip the cans, &c., for gaging or predetermining the extent of the filling of said 85 cans, &c.

The carriage or carrier 6 may be frame-like in general construction for the liquid to readily drip therethrough, with lateral ledges or 90 guides 6^a projecting therefrom into the lateral grooves of the bars or rails 5^a of the guideway 5. This carriage may have pivoted to it at a suitable point a dog 7, adapted to engage the upper edge of the receptacle or tank 100 1 to retain the carriage in position when elevated, as when removing a can, &c., there-

from. The carriage 6 has parallel longitudinal raised bars 6^b, suitably spaced apart, upon which may rest what may be termed a "tray" or "frame" 7^a to receive or hold the can, &c. 5 This tray, however, may be omitted and the cans, &c., be placed directly upon the carriage. Also said carriage has suitably affixed in an elevated position to its lower end a hinged or pivoted lid or cover 6^c, preferably 10 mostly of wire or netting, to hold the can, &c., in place upon the carrier or carriage, the hand of the operator or attendant aiding this purpose. The netting of course will permit the viewing of the contents of the can, &c., to ascertain the extent of the filling thereof. The 15 lid or cover is limited in its movement when thrown backward or off the can, &c., by a projection or stop 6^d, projecting from the carrier or carriage. The carriage itself has a finger-receiving opening 6^e or otherwise adapted to provide for its convenient manipulation or movement by the operator or attendant, as will be readily appreciated.

In event it may be desired to pass the carriage continuously through the tank or thereinto at one end and be removed from its opposite end I provide pulleys or sprocket-wheels 8, one arranged at each end upon a suitable bearing or support 9, secured to said 25 tank, and engage with said pulleys or sprocket-wheels an endless chain or belt 10, which is connected up, as shown, with said carriage. The belt or chain may be returned, with the conveyer, either under the tank or through 30 it, the latter being preferable, to confine the drippings to the tank. Frictional rolls or other guides 11 are suitably disposed within the tank near its bottom to hold down or direct the relatively lower portion of the chain 35 or belt in effecting the dipping operation.

Having thus fully described my invention, what I claim, and desire to secure by Letters Patent, is—

1. In apparatus of the character described, 45 a tank, an adjustable inclined pivoted track or guideway arranged therein, and means adapted to hold the article to be dipped and manipulated along said track, and means for effecting the adjustment of said track, substantially as set forth.

2. In apparatus of the character described, 55 a tank, an inclined pivoted track or guideway arranged therein, means for effecting the vertical adjustment of said track, and means adapted to hold the article to be dipped and manipulated along said tank, and means for effecting the adjustment of said track, substantially as set forth.

3. In apparatus of the character described, 60 a tank, an inclined pivoted track or guideway arranged therein, adjusting-screws adapted to effect the vertical adjustment of said track or guideway, and means adapted to hold the article to be dipped and manipulated 65 along said tank, and means for effecting the

adjustment of said track, substantially as set forth.

4. In apparatus of the character described, a tank, an inclined adjustable pivoted track or guideway arranged therein, and having 70 lateral grooved rails or bars and a carrier or carriage adapted to engage said grooved rails, and be manipulated along the same, and means for effecting the adjustment of said track, substantially as set forth. 75

5. In apparatus of the character described, a tank having means therein for heating it, an inclined track or guideway adjustably arranged in said tank and having laterally grooved rails, and a carrier or carriage adapted to hold the article for dipping and having lateral ledges or extensions adapted to engage said grooved rails, substantially as set forth. 80

6. In apparatus of the character described, 85 a tank having an inclined pivoted track and a carrier or carriage adapted to be manipulated along said track and having a dog adapted to engage said tank at its upper edge, and means for effecting the adjustment 90 of said track, substantially as set forth.

7. In apparatus of the character described, a tank having an inclined pivoted track, a carrier or carriage adapted to be manipulated along said track, and having a lid or cover 95 adapted to engage the article to be dipped arranged upon said carrier, and means for effecting the adjustment of said track, substantially as set forth.

8. In apparatus of the character described, 100 a tank, an inclined track arranged therein, a carrier adapted to be manipulated along said track, a tray arranged upon said carrier, said carrier having a hinged lid or cover adapted to rest upon the article to be dipped, substantially as set forth. 105

9. In apparatus of the character described, a tank having an inclined pivoted track, and a carrier or carriage adapted to be manipulated along said track and having a lid or 110 cover comprising a wire-netting, and means for effecting the adjustment of said track, substantially as set forth.

10. In apparatus of the character described, a tank having an inclined pivoted track or 115 guideway, a conveyer adapted to travel through said tank and connected up to an endless belt or chain compassing pulleys or wheels arranged at the ends of said tank, respectively, and a carrier adapted to be carried by said conveyer, and means for effecting the adjustment of said track, substantially as set forth. 120

In testimony whereof I affix my signature in presence of two witnesses.

FREDERICK STRATTNER.
